UNITED STATES PATENT OFFICE

FRANK BUCHANAN AND ROYAL E. CROSSLEY, OF SYRACUSE, NEW YORK, ASSIGNEES
TO CROUSE-HINDS COMPANY, OF SYRACUSE, NEW YORK, A CORPORATION OF NEW
YORK

LAMP CONSTRUCTION

Application filed January 8, 1929. Serial No. 331,010.

This invention relates to lamps, particularly lamps for illuminating large areas as air ports and has for its object a particularly simple and rigid construction for large lamps suitable for field and air port illumination by which the lamp is readily accessible and adjustable relatively to the focus of the reflector. Other objects will appear throughout the specification.

The invention consists in the novel features and in the combinations and constructions hereinafter set forth and claimed.

In describing this invention, reference is had to the accompanying drawings in which like characters designate corresponding parts in all the views.

Figure 1 is a side elevation of this air port lamp, contiguous portions of a support or pillar being also shown.

Figure 2 is a side elevation, partly broken away, showing the base in its open position and also the light deflector as swung outwardly.

Figure 3 is an enlarged plan view, partly broken away.

Figure 4 is a fragmentary, enlarged side elevation, partly broken away, of the base of the lamp showing the lamp mechanism therein.

Figure 5 is an enlarged transverse sectional view on line 5—5, Figure 1 showing the lower member of the body in plan.

Figure 6 is a plan view of the parts seen in Figure 4.

Figure 7 is an elevation of the detached lamp mechanism.

Figure 8 is a sectional view on line 8—8, Figure 7.

Figure 9 is a fragmentary sectional detail view taken on the plane of line 9—9, Figure 5.

This lamp is of the general type shown in U. S. Letters Patent No. 1,673,100 issued June 12, 1928. The lamp comprises generally, a body, open at its bottom, a reflector carried by the body, a base normally closing the open bottom of the body, lamp mechanism carried by the base and operable to adjust the lamp in juxtaposition with the reflector or the focus thereof, the base being

movable vertically to carry the lamp into and out of the body and reflector, and means connecting the base and the body to support the base and guide the same during its movement.

As here illustrated, the body includes upper and lower members 1 and 2, a reflector between said members, the lower member being open and a base 3 having means for carrying a lamp 4, the base 3 being movable vertically to carry the lamp through the lower member into and out of juxtaposition to the reflector. The reflector is preferably the rear side of a globe 5 of the form shown in the patent above referred to.

The globe 5 is secured at its ends by semi-circular clamping rings 6 and 7, the upper clamping ring 6 being secured to the upper frame member 2 by screws 8 and the lower member being secured by screws 9 to the lower frame member 2. The members 1, 2 are connected by posts or bars 10 located behind the portion of the globe which forms the reflector, and the upper member 1 is secured to the bars 10 as by screws 11, the posts or bars being here shown as tubes, Figure 2, threading into the lower member, and the screws 11 which secure the upper member 1 to the posts thread into plugs 11^a in the upper ends of the posts.

A casing 12 enclosed the reflector part of the globe and the bars 10. The casing is fitted between the top and bottom members 1, 2 and is semi-cylindrical in form and includes front plates 12^a arranged diametrically of the globe and conforming thereto.

The upper member 1 is provided with a visor 13 extending forwardly and overhanging the front side of the globe and a rearwardly extending cap portion 14 closing the upper end of the casing 12.

A plurality of horizontally extending deflectors 15 are suspended from the visor by arms 16 which are pivoted at 17 to the visor, these deflectors having circular cut-outs to conform to the front half of the globe. The deflectors can be swung out of their operative position for the purpose of locating the lamp or lamp filament relatively to the focus of

the reflector and for removing and inserting the globe.

The deflectors are provided with lugs 18 for coacting with pivot screws 19 on the frame members 10 securing the deflectors in their operative position.

The lower frame member 2 is provided with a bracket 20 on the rear side thereof or in any suitable location outside of the path of the opening and closing movement of the base 3, which bracket is formed with means for attachment to a pillar or support 21, it being here shown as provided with a socket for receiving the upper end of a post 21.

The base 3 is connected to the body 1 or the lower member 2 by means which permit it to be lowered and raised vertically to carry the lamp out of and into the body. As here illustrated, the base 3 is cylindrical in general form and formed with an upper portion 23 which telescopes into the lower member 2 and a lower portion 24, these two portions being separated by a horizontal partition 25. The base is also provided with a flange 26 which seats against the lower side of the frame member 2.

The connections between the base and the body are preferably guide rods 27 connected at their lower ends to lugs 28 on opposite sides of the body 3 and extending through guide openings 29 in the lower frame member 2, these rods extending upwardly into two of the tubular posts 10. There are three of these posts 10, two of which are located on opposite sides of the globe 5 nearly diametrically opposite each other. The guide or suspension rods 27 telescope into these two posts. The rods are provided with shoulders 30 at their upper ends and buffer springs 31 are interposed between the shoulder and the member 2. These rods support the base 3 when it is in open position and guide the base during its opening and closing movement.

The base is held in closed position by any suitable latch means as pivot screws 33 pivoted to the frame member 2 and movable into and out of notches in lugs 34 on the base member.

The base member 3 is also formed with an offset boxlike portion 35 large enough to receive a terminal block 35^a connected by wires 35^b to the lamp socket terminal or the terminals of any other lamp support if a socket is not used. The boxlike portion 35 is complementary to a similar boxlike portion 2^a on the member 2. A terminal block 2^b is located in the box portion of the member 2 to the terminals of which the feed wires 36 are connected. The blocks 35^a and 2^b are formed with coacting contacts 35^c and 2^c which separate and break the circuit when the base member 3 is lowered in the position shown in Figure 2.

The lamp mechanism is carried in the up-

per compartment 23 of the base 3 and is adjustable in a plurality of directions to move the lamp vertically and laterally in a plurality of directions to locate it in juxtaposition to the focal point of the reflector. This mechanism comprises a carrier 40 fulcrumed on a raised fulcrum point 41 on the partition 25, and means acting on the carrier at points located in different radii relatively to the fulcrum point 41, which radii are arranged at an angle and preferably an acute angle to each other.

Thus the carrier is in effect provided with angular arms 42, 43 and is fulcrumed at the angle of said arms. The means for adjusting the carrier on its fulcrum point 41 includes screws 44, 45 threading through the partition 25 and thrusting against the lower sides of said arms 42, 43, the adjusting movement being against the action of springs 46, 47 acting on the arms. The screws 44, 45 act independently of each other and by these screws, an adjustment of the lamp or the lamp filament can be effected laterally or horizontally in all horizontal directions.

The springs 46, 47 encircle studs 48, 49 extending through the carrier 40 and threading into the partition 25 and are interposed between heads or nuts 50, 51 on the studs 48, 49 and the carrier 40 or the arms 42, 43 thereof.

The studs 48, 49 preferably extend through the arms 42, 43 of the carrier between its fulcrum point 41 and the adjusting screws 44, 45. The lamp is adjusted vertically by means of a support movable vertically, that is, at an angle to the plane of the carrier 40, this support being movable along upright guides or rods 52 on the carrier, by means of a screw 53 threading through the carrier and connected to the support.

The guide rods 52 are secured at their lower ends in the carrier 40 and at their upper ends in a yoke 52^a supported on the carrier by rods 54.

The support is so arranged that the blocks 51^a which carry the lamp is mounted at an incline out of the vertical so that the lamp filament is located somewhere near the focal point of the reflector. The accurate location of the filament, after the lamp is adjusted to the proper height is determined by operating the screws 44, 45 to tilt the carrier. The support 51 is provided with spaced apart spring pressed roller bearings 55 in each guide rod 52.

The adjusting screws for the carrier and the support have handles located in the compartment of the base below the partition 25. This compartment is provided with a hinged cover 56 which is held in its closed position by a pivot screw 57 cooperating with a notched lug 58 on the cover. The cover 56 may be locked in its closed position and also the base 3 located in its closed position by

means common to both of them as a bar 60 depending from the member 3 and extending through a lug 61 in the margin of the cover, the bar having a hole 62 for receiving a suitable lock member as the hasp of a padlock.

Obviously, by manipulating the screws 44, 45 and 53 to tilt the carrier on its fulcrum point 41 and to move the lamp or support vertically, the lamp filament can be located accurately in the focus of the reflector.

This lamp construction is rigid and strong and consists of but few parts and is particularly adapted for large, heavy lamp units for field or air port illumination.

What we claim is:

1. A lamp comprising a body, a globe carried by the body, the body being open at its lower side, a base having means for supporting a lamp, the base normally closing the open side of the body and movable vertically to carry the lamp into and out of the globe, and means for holding the base in its normal position, the body being formed with a visor overhanging the globe and horizontal deflectors depending from the visor in front of the globe and movable toward and from the globe.

2. A lamp comprising a body, a globe carried by the body, the body being open at its lower side, a base having means for supporting a lamp, the base normally closing the open side of the body and movable vertically to carry the lamp into and out of the globe, and means for holding the base in its normal position, the body being formed with a visor overhanging the globe and horizontal deflectors depending from the visor in front of the globe and movable toward and from the globe, the deflectors having upwardly extending arms pivoted to the visors.

3. A lamp comprising a body including upper and lower members, a globe interposed between said members, the globe having a rear reflector portion, bars connecting said members and supporting the upper member, the bars being located in the rear of the reflector portion, the upper member being formed with a forwardly extending visor overhanging the front side of the globe and a rearwardly extending cap portion, a base normally closing the lower member and having means for supporting a lamp, and being movable vertically to carry the lamp into and out of the reflector of the globe through the lower member, and rods connecting the base and the body, said rods extending through the lower member in the rear of the reflector portion of the globe.

4. A lamp comprising a body and a reflector carried by the body, a base, a rocking carrier fulcrumed on the base and having arms extending at different radial angles to its fulcrum point and means acting on each of said arms and operable independently of each other for rocking the carrier on its ful-

crum, the carrier having means for supporting a lamp.

5. A lamp comprising a body and a reflector carried by the body, a base, a rocking carrier fulcrumed on the base and having arms extending at different radial angles to its fulcrum point and means acting on each of said arms and operable independently of each other for rocking the carrier on its fulcrum, a lamp support mounted on the carrier and adjustable toward and from the same, and means for adjusting the support.

6. A lamp comprising a body provided with a reflector, a base having a fulcrum, a carrier mounted on the fulcrum, screws threading in the base and thrusting against the carrier at points located in different radii arranged at an angle to each other, spring means acting on the carrier to resist movement thereof in one direction by the adjusting means and means carried by the carrier for supporting a lamp in juxtaposition to the reflector.

7. A lamp comprising a body provided with a reflector, a base having a fulcrum, a carrier mounted on the fulcrum, screws threading in the base and thrusting against the carrier at points located in different radii arranged at an angle to each other, spring means acting on the carrier to resist movement thereof in one direction by the adjusting means, a lamp support carried by the carrier and movable in a direction at an angle thereto and means carried by the carrier for adjusting the lamp support.

8. A lamp comprising a body having a reflector, a base, means carried by the base for supporting the lamp in juxtaposition to the reflector, said means comprising a carrier having a pair of radial arms arranged at an angle to each other, the carrier being fulcrumed on the base at the angle of said arms, spring means acting on said arms to press the carrier against its fulcrum point, and means operable independently of each other and acting on said arms to move the carrier on its fulcrum point.

9. A lamp comprising a body having a reflector, a base, means carried by the base for supporting the lamp in juxtaposition to the reflector, said means comprising a carrier having a pair of radial arms arranged at an angle to each other, the carrier being fulcrumed on the base at the angle of said arms, spring means acting on said arms to press the carrier against the fulcrum point, and means operable independently of each other and acting on said arms to move the carrier on its fulcrum point, the carrier being formed with a guide arranged at an angle to the plane of said radial arms, a lamp support movable along the guide and means carried by the carrier for moving the lamp support along the guide.

10. A lamp construction comprising a bot-

tom member formed with a segmental flange and having a cylindrical flange depending from the inner edge of the segmental flange, supporting members extending from the segmental flange portion of the bottom member, a circular top member mounted upon the supporting members, the rear portion of the top member conforming to the periphery of the segmental flange portion of the lower member, 5 a base carrying a lamp support and movable vertically into and out of the depending circular flange of the bottom member, and means carried by the base and extending through the bottom member to guide the base into and 10 out of the bottom member.

11. A lamp comprising a body including upper and lower members and bars between said members, a concave reflector interposed between and abutting at its ends against said 20 members, the lower member having an opening, a base normally closing said opening and having means for supporting a lamp, the base being movable vertically to carry the lamp into and out of the reflector through the opening in the lower member, the upper member extending in the rear of the reflector and also to the front thereof whereby it forms a hood overhanging the lamp, the lower member having a front rim portion confining the greater part 25 of the lamp receiving opening and a rearward segmental flange portion, said bars extending between the rear portions of the upper and lower members, and means for guiding the base, said means extending through said segmental flange portion in the rear of the reflector.

12. A lamp comprising a lower member having means for adjustably mounting the same upon a support, an upper member, the 40 rear portion of which conforms to the rear portion of the lower member and the front portion projecting forwardly to form a visor for the lamp, upright members connecting the upper member with the lower member, said 45 members also having depending circular flanges in alinement, a reflector mounted between said flanges, a base movable into and out of the lower member and having an adjustable lamp support and means extending outside of 50 the base for adjusting said lamp support without removing the base from the lower member.

13. A lamp construction comprising a lower member, an upper member, connecting bars 55 between said members, the lower member comprising a segmental flange having a circular flange depending from its inner arc and having a box section depending from a portion of the segmental flange, a reflector 60 mounted between the upper and the lower members and in front of said bars, a circular base movable vertically into and out of the lower member and being formed with a box section at one side thereof, and having a lamp 65 support, contacts mounted within the box sec-

tion of the lower member and being connected to a feed circuit, complementary contacts mounted in the box portion of the base and connected to the lamp, and means for guiding the base so that the contacts on the base will engage the contacts on the lower member when the base is moved in said member.

In testimony whereof, we have hereunto signed our names at Syracuse, in the county of Onondaga, and State of New York, this 31st day of December, 1928.

FRANK BUCHANAN.
ROYAL E. CROSSLEY.
